COMBINED MONEY CLIP AND STAMP HOLDER

Eugene Schildkraut, Great Neck, N. Y.

Application January 9, 1953, Serial No. 23,082

Term of patent 7 years

(Cl. D87—3)

To all whom it may concern:

Be it known that I, Eugene Schildkraut, a citizen of the United States, residing at town of Great Neck, in the county of Nassau and State of New York, have invented a new, original, and ornamental Design for a Combined Money Clip and Stamp Holder, of which the following is a specification, reference being had to the accompanying drawing, forming part thereof.

In the drawing

Fig. 1 is a top plan view of a combined money clip and stamp holder showing my new design;

Fig. 2 is a front view;

Fig. 3 is a left side view of Fig. 2;

Fig. 4 is a right side view of Fig. 2;

Fig. 5 is a bottom plan view; and

Fig. 6 is a perspective front view with the stamp holder in an open position.

I claim:

The ornamental design for a combined money clip and stamp holder, substantially as shown and described.

EUGENE SCHILDKRAUT.
